UNITED STATES PATENT OFFICE.

GEORGE W. HOBBS, OF LOS ANGELES, CALIFORNIA, ASSIGNOR OF ONE-HALF
TO ALBERT J. PARTRIDGE, OF SAME PLACE.

NAIL OR TACK DRIVER.

SPECIFICATION forming part of Letters Patent No. 653,772, dated July 17, 1900.

Application filed October 14, 1898. Serial No. 693,528. (No model.)

To all whom it may concern:

Be it known that I, GEORGE W. HOBBS, a citizen of the United States, residing at Los Angeles, in the county of Los Angeles and 5 State of California, have invented new and useful Improvements in United Nail or Tack Drivers, of which the following is a specification.

My invention relates particularly to improvements upon a certain united nail or tack driver described in Letters Patent of the United States No. 613,569, granted to me November 1, 1898.

The particular object of my invention is to provide means whereby the nail or tack which is severed from the strip will be only partially driven at the first operation of the punch, so that the nail thus only partially driven may be engaged by the end of a race-way or switch which I provide in the head of the nailer, the nail thus acting as a stop or gage to regulate the distance apart at which the nails will be driven, but being in position to be engaged by the punch at its next operation and to be then fully driven home.

A further object of my invention is to provide an automatic gage whereby when desired to gage the distance of the nails from the edge of the article to be nailed, but so arranged as to present no obstruction to the use of the tacker upon a broad flat surface.

A further object of my invention is to provide an improved punch for severing the nails or tacks from the strip and driving them.

35 A further object of my invention is to provide an improved arrangement for operating the punch, so that the stroke which is delivered upon the punch to sever and drive the nail or tack will operate to hold the tacker firmly down upon the article to be nailed or tacked before the hammer or driving device comes into contact with the head of the punch or punch-stock.

45 My invention comprises the various features of construction and combinations of parts hereinafter fully set forth and claimed.

The accompanying drawings illustrate my invention.

Figure 1 is a fragmental perspective view 50 of a device embodying my invention. Fig. 2 is a sectional view of the device along the nail-

strip on line indicated by 2 2, Figs. 3 and 5, showing one nail set—i. e., partially driven into a shoe-sole—and the parts ready for a second blow of the hammer to sever and set 55 a second nail and to fully drive home the nail which is shown partially driven. Fig. 3 is a sectional view of the tool at right angles to that shown in Fig. 2, being across the line of the nail-strip on line indicated by line 3 3, 60 Figs. 2 and 5. The section through the shoe-sole in each instance is along the line of nails and not on the lines 2 2 or 3 3, which indicate the lines on which the tool is sectioned. In Fig. 3 the parts are in position with one nail 65 fully driven and a second nail set. In this view the tacker is shown applied to a shoe-sole to set the nails with the longer axes of their heads crosswise the line of driven nails—that is to say, crosswise a line parallel with 70 the edge of the sole—while in Fig. 2 the tacker is applied to set the nails with the longer axes of their heads lengthwise the line of driven nails—that is, parallel with the edge of the sole. It is to be understood that in 75 each of the views Figs. 2 and 3 the sight is directed toward the edge of the sole, and in practical operation the movement of the tacker will be toward the left of said views. Fig. 4 is a perspective view of the punch and 80 punch-stock removed from the punch-box. Fig. 5 is a fragmental view looking at the bottom of the outer end of the tacker. In this view the end which is uppermost corresponds to the right-hand end of Fig. 2, and the strip 85 of nails N are shown in place and hide the shoulder d." Fig. 6 is a fragmental sectional view on line indicated by 6 6, Fig. 5, showing my drop-gage. Fig. 7 is a perspective view of the cut-off and its actuating-lever removed from the machine. Fig. 8 is a perspective view of the punch removed from the punch-stock.

In the drawings, A represents the nail-chamber, which is the same as that shown 95 and described in my former application for patent.

B is the punch-box, which is secured upon the head or outer end Q of the device by means of screws b.

C is the punch-stock, which is provided with 100 a slot c, within which is seated the punch D.

The punch is secured in its seat by means of a set-screw D'. The punch comprises two members d d', arranged at right angles with each other and provided with a slot d'', with 5 in which the stop a, which is provided across the raceway, is chambered as the punch is forced down to sever and drive the nail. One of these members d' is provided with a shoulder or cutting edge d''', arranged sufficiently 10 above the bottom of the punch to allow the bottom of the punch to engage with the face of the article to be nailed when the nail which has just been severed is only partially driven, as indicated in Fig. 3. It will be ob- 15 served that in my device the punch may be as wide and thick as is necessary to secure strength, since each nail is started into the article to be nailed before it is completely severed from the nail-strip.

20 E is the cut-off, which is provided with a cut-off tongue e, which is adapted to enter between the nail to be severed and the adjoining nail, and is also provided with a tongue e', which enters between the second and third 25 nails to prevent the nail-strip from drawing back after the first nail is severed and before the shuttle has time to be forced back and to engage with the strip to feed it forward. This cut-off is operated by means of a lever 30 e'', which is pivoted to the body of the cut-off and is also pivoted to the tacker by a pivot e'''. The upper end of this lever is pro- 35 vided with an antifriction-roller e''', which travels in a cam-raceway c', which is pro- 40 vided in the punch-stock. In Fig. 7 the cut-off E is alike at both ends, so that in case the tongue e or the tongue e' at one end of the cut-off is broken the cut-off can be turned on its pivot 2 to bring the other end into position for use.

F is a cam-wedge which operates the shuttle in the same manner as shown in my former application for patent, and therefore detailed description of the shuttle and the 45 means for operating it are not given herein.

The head Q of the nailing device is provided with two nail switches or raceways G G', which are arranged at substantially right angles with each other and also serve to allow 50 the punch to reciprocate as the nails are driven. The raceway G is simply an onward extension of the main nail raceway or slot G'', which leads from the nail-chamber into the head of the device, and the raceway or switch 55 G' is a lateral extension of G'', arranged at substantially right angles therewith. Thus when the nail is severed and partially driven, as indicated in Fig. 2, as soon as the punch moves upward out of the raceway, as shown 60 in said figure, the nailing device may be slipped lengthwise (to the left in Fig. 2, right in Fig. 1, and down in Fig. 5) along upon the article being nailed, the raceway G permitting the nailer to move in line with the nail- 65 raceway G'' until the end of the raceway G engages with the nail and stops the forward motion of the nailer. At the next operation

of the punch this partially-driven nail is fully driven, while the punch at the same operation severs and partially drives another nail, 70 which in turn acts as a gage for the succeeding nail.

When the tacker is applied as shown in Fig. 3, the operation is substantially the same as above stated, except, however, that the 75 tacker is moved sidewise instead of lengthwise, so that the side switch or raceway G' receives the nail, and the end of G' serves as the stop for the nail. When moved lengthwise, as in Fig. 2, the member d of the punch 80 completes the driving of the nail. When the tacker is moved crosswise, as in Fig. 3, the member d' completes the driving of the nail.

I provide improved means for gaging the distance from the edge of the article being 85 nailed at which the nails shall be driven. These means consist of automatic gages H H' H'', which by the action of gravity drop into operative position when the nailer is placed in a horizontal position, as shown in 90 Fig. 6, but may be retracted and chambered in the nailer by engagement with the face of the article to be nailed when their use is not desired. These gages are preferably round pins, which are each provided at the top with 95 a head or an enlargement h and slide in guideways h'. These guideways are each enlarged at the upper end to receive the head of its respective pin, so that the pins may play freely in the guideway and yet fit tightly 100 therein, so as to avoid any side play of the gages when in use. When it is desired to use the gage H, the gages H' H'' will engage with the face of the article to be nailed and will be thereby pushed up into the head out 105 of the way. If it is desired to use the gage H', the gages H H'' will be pushed up out of the way, and if it is desired to drive the nails at a distance from the edge greater than the 110 distance of any of the gages from the nail to be driven all the gages may be retracted by laying the head of the nailing device flat upon the point desired.

In order to provide means whereby the nailing device may be firmly held down upon 115 the article to be nailed as the nails are being driven, I provide a guide I, which is secured to the punch-box and extends upward therefrom. Mounted upon this guide I arrange a hammer or plunger J, and in this plunger I 120 provide a chamber j, within which is chambered a coiled spring J' when the plunger is forced downward to operate the punch. I have shown this guide provided with two 125 members arranged parallel with each other in order to prevent any cramping or binding of the plunger in its reciprocation.

In practical operation, the parts being assembled as shown in Fig. 1, the plunger is forced downward to strike the head of the 130 punch-stock, thus forcing the punch downward until the roller e''', working in the cam-slot c', forces the cut-off E into position with the operating cut-off tongue e between the

first nail of the strip and the second nail thereof, the operating-tongue *c'* entering between the second and third nails. The same movement brings the cutting edge of the 5 punch into engagement with the first nail and severs it from the web and partially drives it, so that it assumes the position shown at *N'*, Figs. 2 and 3. The spring *J'*, acting against the head of the punch-box as the plunger de- 10 scends to deliver its blow to the punch, holds the nailer firmly down upon the work and insures that the point of the nail will be sufficiently close to the face of the work to enter such face before the nail is fully severed 15 from the web. This spring also aids in returning the hammer or plunger to its elevated position, and as soon as the punch is relieved from the hammer the spring *K* forces the punch-stock upward, thus elevating the 20 punch, and as the punch rises above the nail-strip the shuttle feeds such strip forward against the stop *a* ready for a second nail to be severed and partially driven. After the first nail is driven the operator gently pushes 25 the nailer constantly along the line where the nails are to be driven, and as the device moves along the nail which is partially driven is received by the appropriate raceway, the end of which finally engages with the nail, 30 and thereby stops the movement of the nailer. Then a second blow is delivered upon the punch-stock and a second nail is severed from the strip and partially driven, while the long end of the punch engages the previously par- 35 tially-driven nail and fully drives it, as at *N''*. The operation just described is repeated until a sufficient number of nails have been driven. After the nail has been severed from the nail- 40 strip the tongue prevents the strip from mov- ing back out of the path of the shuttle.

Now, having described my invention, what I claim as new, and desire to secure by Letters Patent, is—

1. In a continuous-nailing device, the combination set forth of the head of the device: guideways provided in such head: and independent drop-gages working in such guideways and adapted to project from such head, or to be retracted and chambered in the head. 45
2. In a continuous-nailing device, the combination set forth of the nail-punch: the guide secured to the punch-box: the coiled spring encircling the guide: and the hammer or plunger working upon the guide to strike the nail-punch and provided with the chamber 50 to receive the coiled spring.
3. In a continuous-nailing device, the com- 55

bination set forth of the nail-punch; the punch-box; the guide comprising two parallel members fixed to the punch-box and projecting upwardly therefrom; a coiled spring encircling each member of the guide; and a hammer or plunger working upon the guide to strike the punch. 60

4. In a continuous-nailing machine, the combination set forth of the punch-box: the punch-stock arranged to reciprocate in the punch-box: the punch provided with a nail severing and setting shoulder arranged at such a distance above the bottom of the punch 70 as to only partially drive the nail by the time the bottom of the punch engages with the face of the article to be nailed: and the head of the nailing device, provided with a slot to receive the punch and to form a raceway for 75 the partially-driven nail.

5. A continuous-nailing device of the character set forth comprising a head provided with a slot to receive and chamber the head of a partially-driven nail; a punch-stock provided 80 with a cam-slot; a punch secured to the punch-stock and working in the slot of the head and provided on its front edge with a cutting and setting shoulder arranged at such a distance above the bottom of the punch 85 that a nail severed by such shoulder will be only partially driven when the bottom of the punch is in engagement with the face of the article to be nailed; a cut-off provided with a tongue to enter between the first nail and the 90 succeeding nail of a nail-strip; and a pivoted lever for operating the cut-off, provided at its top with an antifriction-roller working in the cam-slot in the punch-stock. 95

6. In a nailing device, the punch set forth comprising two members secured together at substantially right angles with each other with a stop-receiving slot between them, one of the members being provided with a nail severing and setting shoulder at the edge of 100 the slot and above the bottom of the punch.

7. In a nailing device, the combination of the head of the device provided with the raceway: the stop arranged across the raceway: the switch being a lateral extension of the 105 raceway: and the punch comprising two members secured together at substantially right angles with each other to operate in the raceway and switch and provided with the slot to straddle the stop.

G. W. HOBBS.
